(57) **CLAIM**

I claim the ornamental design for a stud interlock component, as shown and described.

DESCRIPTION

FIG. 1 is a front/right/top perspective view of the stud interlock component showing my new design, shown broken in the center with a double line to indicate that no particular length is claimed.

FIG. 2 is a right side elevation view thereof. The left side is identical to the right side.

FIG. 3 is a front view thereof. The rear view is identical to the front view.

FIG. 4 is a top view thereof; and,

FIG. 5 is a bottom view thereof.

The double line shown in FIG. 1 forms no part of the claimed design. In addition, the shading lines shown in all of the drawings represent the approximate three-dimensional contour of the design, and thus are not intended to indicate surface decoration.
